CLAIM

The ornamental design for a shoulder towel assembly, as shown and described.

DESCRIPTION

FIG. 1 is a top front side perspective view of a shoulder towel assembly showing my new design;

FIG. 2 is a front view of the shoulder towel assembly;

FIG. 3 is a bottom side view of the shoulder towel assembly;

FIG. 4 is a top view of the shoulder towel assembly;

FIG. 5 is a rear view of the shoulder towel assembly;

FIG. 6 is a right side view of the shoulder towel assembly;

FIG. 7 is a left side view of the shoulder towel assembly; and,

FIG. 8 is a disassembled view of the shoulder towel assembly.

The broken lines are illustrative of stitching forming part of the claimed design.
